CLAIM

The ornamental design for a shelf support post, as shown and described.

DESCRIPTION

FIG. 1 is a perspective view of a shelf support post, showing my new design;

FIG. 2 is a side elevational view, the opposite side being the same in appearance as the side shown;

FIG. 3 is an outer elevational view;

FIG. 4 is an inner elevational view; and

FIG. 5 is a top view, the bottom being the same in appearance as the top.
